SHOE CALK

Brennan B. West, Cleveland, Ohio

Application June 27, 1934, Serial No. 732,632

7 Claims. (Cl. 36—67)

This application is a continuation of one filed on the 17th day of February, 1931, Serial No. 516,373, now Patent No. 1,975,133, issued October 2, 1934, as to all subject matter which is common to the two applications.

The invention is an improved calk for use on the soles and heels of golf shoes, hunting and hiking boots, and other footwear, and its general objects are to provide a device of this character that may be easily and quickly attached to the sole or heel of a boot or shoe by an operation equivalent to that of driving a nail and that will hold very securely within the material of the sole or heel. Further, to provide a shoe calk that is simple and relatively economical of manufacture, and, more limitedly, to provide a composite shoe calk comprising a solid stud or spike adapted to be produced on automatic machines at low cost, and a pronged ferrule that consists of a relatively inexpensive sheet metal stamping, the parts being adapted to be assembled in the process of applying.

By making the calk of two separate parts, materials especially suited for the respective parts may be selected. For example, the spike or stud, which is subjected to hard wear, may be made of very tough steel or other material, or it may be hardened after it is made, and the ferrule, which has a number of prongs, preferably six, that are beveled desirably on their inner sides at their ends so that they will spread apart as they enter the leather and thus hold securely in the manner of a rivet and without penetrating the sole or having to be clenched on a last, may be produced of a grade of sheet steel especially suited to the purpose.

In the drawing accompanying and forming a part hereof, Fig. 1 is a perspective view showing one of the calks applied to the toe of a boot or shoe; Fig. 2 is a sectional detail showing the manner in which the prongs of the ferrule spread when driven into the leather; Figs. 3 and 4 are elevational views, respectively, of the ferrule and stud; Fig. 5 shows the ferrule and stud resting upon a surface to which the calk is to be applied with the stud held central of the ferrule by cooperation of its head with the prongs of the latter, the view including also the tool used in driving the ferrule, the ferrule and adjacent end of the tool being in section; Fig. 6 shows the bottom of a boot or shoe to which a set of calks are applied; and Fig. 7 is a detail of a modified form of the calk.

The calk is designated generally by the reference character A, and its component parts, i. e. the ferrule and stud, are designated B and C, respectively. The ferrule is drawn from sheet metal of suitable gauge and quality to a generally frusto-conoidal shape, an opening b being punched or otherwise formed in its smaller end

in such manner that the material surrounding its outer end is reduced to a feather edge. Prongs b', preferably six in number, project from the larger end of the ferrule in parallel relation to each other and spaced equi-distant about the circumference of the ferrule. The ends of the prongs are beveled or chamfered, desirably on their inner sides, as indicated at b², for a purpose that will presently appear.

The stud or spike C has a head c at one end and is tapered at the other, as indicated at c', the body portion of the stud being straight or cylindrical, as shown at c². According to the present embodiment, the head c is circular and flat. The opening b of the ferrule is of a size 10 to receive snugly the body portion c² of the stud, and the head c closely fits within the interior of the larger end of the ferrule, and when forced as far as it will go into the same the circular face of the head is substantially flush with the 15 edge of the larger end of the ferrule, and the angle between the body portion and the tapered end of the stud is about coincident with the feather edge of the smaller end of the ferrule. The taper of the external surface of the smaller 20 end of the ferrule blends into the taper of the stud when the parts are properly assembled.

In applying the calks to the sole and heel of a boot or shoe, marks may be made at the points where the calks are to be located and the boot or shoe disposed on a last. A stud or spike is then placed in position on the sole or heel, with a ferrule engaged over it, and the tool D is applied, as indicated in Fig. 5. The tool is tubular, or is provided with a socket d, and the annular end of the tool is engaged with the shoulder between the larger and smaller ends of the ferrule, the tapering smaller end guiding the tool to its seat upon the shoulder. It will be observed that the shoulder is substantially in alignment with the 30 prongs b'. Now by pounding the tool with a hammer or the like, in the manner of driving a nail, the prongs may be driven into the leather, the stud, in the meantime, being retained central within the ferrule by the engagement of the 35 prongs with its head. In this connection, it will be noted that the chamfer or bevel on the prongs is no greater in depth than the thickness of the head c. As the prongs enter the leather they are caused to flare outwardly by the camming 40 action of their chamfered or beveled ends, and a very secure holding of the prongs within the leather is assured, and penetration of even a 45 relatively thin sole by the prongs is avoided.

When the stud and ferrule attain their final 55 assembled condition, the former fits very tightly within the latter and the calk, as a whole, is rigid upon the sole or heel. The tapered, smaller end of the ferrule serves not only as a guide for properly positioning the tool upon the shoulder 60

of the ferrule, but it greatly assists in firmly holding the stud perpendicular to the surface to which the calk is applied, notwithstanding the very severe side thrusts imposed upon the calk 5 when in use.

Fig. 7 shows the original form of the composite calk as disclosed in the parent application hereinbefore referred to. The ferrule F, in this case, has a central opening f for the accommodation 10 of the body portion g² of the stud G. It is dished to receive the head g of the stud and is provided with four prongs f' that are chamfered or beveled at f².

Having thus described my invention, what I 15 claim is:

1. A shoe calk consisting of a solid metallic stud, and a separate sheet metal ferrule, adapted to be assembled in the process of applying; the stud having a flat head and a straight body portion 20 adjacent the same, and the ferrule having an opening for the reception of the straight body portion of the stud and formed about said opening to receive the head, the ferrule being provided with a plurality of prongs extending from its 25 edge in parallel relation to each other and spaced about a circle corresponding substantially to the circumference of the head, the ferrule being adapted to be placed over the stud with its prongs engaging a surface into which they are to be driven through the intervention of a socketed tool applied to the ferrule, the prongs cooperating with the head of the stud to retain the stud central of the ferrule during the driving operation, the ends of the prongs being chamfered on their 30 inner sides to a depth not exceeding the thickness of the head.

2. A shoe calk consisting of a solid metallic stud, and a separate sheet metal ferrule, adapted to be assembled in the process of applying; the stud comprising a body portion provided with a head at one end, and the ferrule having an opening for the reception of the body portion of the stud and formed about said opening to receive the head, the material of the ferrule surrounding 45 the opening being projected so as to extend a substantial distance along the body portion of the stud, the ferrule being provided with a plurality of prongs extending from its edge.

3. A shoe calk consisting of a solid stud, and a 50 separate sheet metal ferrule, adapted to be assembled in the process of applying; the stud having a straight body portion provided with a head at one end and tapered at the other, and the ferrule having an opening for the reception of the 55 straight body portion and formed about said opening to receive the head, the material of the ferrule surrounding the opening being projected so as to extend a substantial distance along the body of the stud and tapering off to a feather edge so that the exterior surface of the ferrule merges into that of the tapered end of the stud, the ferrule being provided with a plurality of prongs 60 extending from its edge in parallel and closely spaced relation to each other about a circle corresponding substantially to the circumference of the head.

4. A shoe calk consisting of a solid metallic stud, and a separate sheet metal ferrule, adapted to be assembled in the process of applying; the 70 stud comprising a body portion provided with a head at one end, and the ferrule having an open-

ing for the reception of the body portion of the stud and formed about said opening to receive the head, the material of the ferrule surrounding the opening being projected so as to extend a substantial distance along the body portion of the stud, the ferrule being provided with a plurality of prongs extending from its edge in parallel and closely spaced relation to each other about a circle corresponding substantially to the circumference of the head, the ends of the prongs being 5 chamfered. 10

5. A shoe calk consisting of a solid stud, and a separate sheet metal ferrule, adapted to be assembled in the process of applying; the stud having a straight body portion provided with a head 15 at one end and tapered at the other, and the ferrule having an opening for the reception of the straight body portion and formed about said opening to receive the head, the material of the ferrule surrounding the opening being formed to extend a substantial distance along the body of the stud and tapering off to a feather edge so that the exterior surface of the ferrule merges into that of the tapered end of the stud, the ferrule being provided with a plurality of prongs 20 extending from its edge in parallel and closely spaced relation to each other about a circle corresponding substantially to the circumference of the head, the ends of the prongs being chamfered 25 on their inner sides to a depth not exceeding the 30 thickness of the head.

6. A shoe calk consisting of a solid metallic stud and a separate sheet metal ferrule, adapted to be assembled in the process of applying; the stud having a head at one end and being tapered 35 at the other, and the ferrule consisting of a substantially frusto-conoidal shell having an opening in its smaller end arranged to snugly receive the body portion of the stud and recessed to accommodate the head thereof, the external surface of the smaller end of the ferrule merging into the tapered end of the stud when the parts are assembled, the ferrule being provided with a plurality of prongs extending from its larger 40 end in parallel relation to each other, there being a shoulder about the outer side of the ferrule in substantial alignment with the prongs 45 onto which the perimeter of a socketed or tubular tool is adapted to be guided by engagement with the smaller end of the ferrule. 50

7. A shoe calk consisting of a solid metallic stud, and a separate sheet metal ferrule, adapted to be assembled in the process of applying; the stud having a flat head at one end of its body portion, and the ferrule having an opening for 55 the reception of the body portion of the stud and formed about said opening to receive the head, the ferrule being provided with a plurality of prongs extending from its edge in parallel relation to each other and spaced about a circle corresponding substantially to the circumference of the head, the ferrule being adapted to be placed over the stud with its prongs engaging a surface into which they are to be driven through the intervention of a socketed tool applied to the ferrule, the prongs cooperating with the head of the 60 stud to retain the stud central of the ferrule during the driving operation, the ends of the prongs being chamfered on their inner sides to a depth not exceeding the thickness of the head. 65
